CAR CONSTRUCTION

George E. Dath, Mokena, Ill., assignor to W. H. Miner, Inc., Chicago, Ill., a corporation of Delaware

Application May 13, 1944, Serial No. 535,454

9 Claims. (Cl. 105—200)

This invention relates to improvements in car construction.

One object of the invention is to provide an improved construction for railway cars having the usual body and truck bolsters connected by a center pin, wherein the pin is expandable and shoulders against the bolsters to connect the bolsters for swiveling movement and lock the same against vertical separation.

Another object of the invention is to provide a sectional center pin of the character indicated, wherein the parts or sections of the pin are provided with filler projections for holding the sections thereof spread apart, thereby eliminating the separate filler or spreading element employed in the usual sectional center pin.

A further object of the invention is to provide a sectional center pin as set forth in the preceding paragraph, wherein the sections are spread apart by relative lengthwise displacement of the same with respect to each other.

A still further object of the invention is to provide a center pin for railway car trucks connecting the body and truck bolsters, comprising two elongated sections or parts extending through the center pin receiving openings of the bolsters, each section being headed at opposite ends to shoulder against the bolsters at said openings, wherein the sections are provided with means integral therewith for camming the sections apart during application of the pin to the bolsters, and hold the same in spread condition, thereby maintaining the pin expanded with the heads thereof shouldered against the bolsters.

Yet another object of the invention is to provide a center pin for railway car trucks connecting the body and truck bolsters, comprising two sections headed at opposite ends to overhang the bolsters at the center pin receiving opening thereof, wherein each of said sections is provided with an inward enlargement or projection at one end thereof and the inward projections on said two sections are respectively at opposite ends of the pin and the projection of each section bears on the inner side wall of the opposed section, the projections being brought into operative spreading relation by relative lengthwise displacement of said sections.

Other objects of the invention will more clearly appear from the description and claims herein-after following.

In the drawings forming a part of this specification, Figure 1 is a top plan view of the central portion of a railway car truck at the body bolster thereof, illustrating my improvements in con-

nection therewith. Figure 2 is a longitudinal, vertical sectional view, corresponding to the line 2—2 of Figure 1. Figure 3 is a transverse, horizontal sectional view, corresponding substantially to the line 3—3 of Figure 2. Figure 4 is a bottom plan view of Figure 2, looking upwardly in said figure. Figures 5 and 6 are views, similar to Figure 2, illustrating the manner of applying my improved center pin construction to the bolsters of a railway car. Figures 7 and 8 are detail perspective views respectively of the two sections of my improved center pin construction. Figure 9 is a view, similar to Figure 2, showing the pin applied from the top of the body bolster. Figure 10 is a view, similar to Figure 2, illustrating another embodiment of the invention.

In said drawings, 11 indicates the body bolster of the car and 12 the truck bolster. The body bolster is of the cast type and has diaphragm sections 13—13, top and bottom walls 14—14, and a center section 15 to accommodate the center pin. The section 15 is of cylindrical, tubular form, as shown, and has an annular, inwardly projecting flange 16 between the top and bottom ends, thereby providing an annular shoulder 17. The opening 18 defined by this flange is circular in form and of slightly greater diameter than the shank of the center pin. The truck bolster 12, which is also preferably a casting, has top and bottom walls 20 and 21, connecting side webs 22—22, and spaced, vertical walls 23—23. The spaced walls 23—23 define a pocket 24 therebetween, which serves to accommodate the bottom head of the center pin connecting the bolsters. The top wall of the truck bolster is provided with an upstanding, hollow boss in the form of an annular flange 25 which projects into, and is accommodated within, the lower end of the tubular center section 15 of the body bolster 11. The opening 26, defined by the flange 25, is in axial alignment with, and corresponds in diameter to, the opening 18 provided by the flange 16 of the tubular section of the bolster 11. The usual bearing plate or shim 27 is interposed between the body and truck bolsters.

Referring first to the embodiment of the invention illustrated in Figures 1 to 9 inclusive, the body bolster is interlocked with the truck bolster by my improved locking center pin which comprises broadly two elongated sections or members A and B, which are headed at opposite ends. The two members A and B are of the same design, except as hereinafter pointed out. Each member is of substantially semi-cylindrical cross section and is provided at the top thereof with an ec-

centric, substantially semi-cylindrical, outstanding flange 28, and with a concentric, substantially semi-cylindrical, outstanding flange 29 at the bottom end thereof. As will be evident, the flanges 28 and 29 form top and bottom head members of the members A and B, which head members are at opposite ends of the shank portions of said members A and B.

On the inner side, each member A and B presents a substantially flat, vertically extending, transverse face 30. The member A has a laterally inwardly extending flange or lug 31 at the lower end thereof, projecting from the inner side, and the flat face 30 of said member extends from said lug to the upper end thereof. The lug 31 has its underneath face in transverse alignment with the underneath face of the flange 29 at the lower end of said member, and is cut away on an incline, or beveled off at the upper side, as indicated at 32. The transverse, vertical side face 30 of said lug is substantially flat and, in the applied condition of the pin, bears on the flat, inner side face 30 of the member B at the lower end of the latter. The member B is provided with a laterally inwardly extending flange or lug at the upper end thereof, projecting from its inner side, which lug is similar to the lug 31 of the member A and is also indicated by 31. The lug 31 of the member B bears on the inner side of the member A, that is, on the flat surface 30 thereof.

As will be evident, the lugs 31—31 of the members A and B hold these members spread apart with the heads or flanges 28—28 overlapping the annular shoulder 17 provided by the flange 16 of the body bolster 11 and the flanges 29—29 cooperating with the shoulder presented by the top wall of the pocket 24 of the truck bolster 12 to restrict upward movement of the pin.

As shown most clearly in Figures 2 and 7, the member A is beveled off at the upper end on the inner side to provide an incline or cam face 33. The inclined faces 32—32 of the flanges or lugs 31—31 of the members A and B, and the inclined face 33 of the member A are parallel to each other. The inclined face 32 on the underneath side of the lug 31 of the member B forms a cam face cooperating with the cam face 33 of the member A to cam the upper end of the latter outwardly, and the inclined face 32 at the lower end of the member A forms a cam face cooperating with the lower end of the member B to cam said member A outwardly at its lower end during application of the center pin to the bolsters, as hereinafter pointed out.

The eccentric flanges 28—28 at the top ends of the members A and B are of such a size that they will pass freely through the pin receiving openings of both the body and truck bolsters when the pin is contracted, that is, the top head of the member B is of such a size and outside contour that it will pass freely upwardly and downwardly through the center pin receiving openings of the bolsters when the member A is absent, and the head of the member A is of such a size and outside contour that it will pass freely through said openings when the pin is contracted with the member B in position and with the inner side of the member A abutting the inner side of the member B.

In applying the center pin, the member B is first inserted in the center pin openings of the bolsters by passing the same upwardly through said openings until the upper head or flange 28 thereof reaches a position above the shoulder 17

of the body bolster. When thus disposed, the member B is displaced laterally outwardly to engage the flange 28 thereof over said shoulder, as shown in Figure 2, and the flange 29 beneath the shoulder of the opening of the truck bolster. The member A is then inserted upwardly in the bolster openings in parallelism with the member B, as illustrated by the dotted line position of the member A in Figure 5. As the member A is pushed upwardly, the lower end thereof is cammed outwardly by engagement of the cam face 32 thereof with the lower end of the member B, and the upper end of said member A comes into engagement with the underneath side of the lug 31 at the upper end of the member B, as shown in full lines in Figure 5. Through this tilting movement of the member B, the head or flange 28 at the upper end thereof is angled to position the outer edge of said flange slightly above the shoulder 17 of the bolster. During this operation, the upper end of the member A is cammed laterally outwardly away from the member B by the cam face 33 of the member A engaging with the underneath cam face 32 of the member B, thereby engaging the head or flange 28 of the member A over the shoulder 17, as shown in Figure 6, at the same time permitting the member B to drop to the position shown in Figure 2. The upper end of the pin is thus held spread apart by the lug 31 while the lower end is held in spread condition by the lug 31 of the member A abutting against the inner side of the member B. With the heads 28—28 at the upper ends of the sections A and B resting on the shoulder 17 of the body bolster, the pin will be maintained in the spread condition shown in Figure 2, locking the bolsters together. The weight of the member B of the pin will effectively prevent the same from working upwardly to a position wherein the upper head end of the member A could slip below the lug 31 of the member B. However, in order to guard against any possibility of such action taking place, the member B may be provided with a depending perforated lug 34 at its lower end adjacent the inner side, through which a bolt 35 is engaged, the nut 36 of which shoulders against the lower end of the member A. Upward movement or displacement of the member B with respect to the member A is thus positively prevented.

In removing the center pin from the bolsters, the operation is substantially the reverse of that just described, the member B being pushed upwardly until it provides sufficient clearance for displacement of the head member 28 and the lug 31 of the member A to permit the latter to swing to the full line position shown in Figure 5 and drop out or be forcibly pulled downwardly.

Referring next to the embodiment of the invention illustrated in Figure 10, my improved center pin comprises two members C and D which differ slightly from the members A and B hereinbefore described. The members C and D are provided with outstanding flanges 128—128 at their upper ends which are in all respects similar to the flanges 28—28 of the members A and B hereinbefore described, with the exception that the underneath faces of the flanges are beveled, as indicated at 137 to fit the correspondingly beveled surface 138 of the shoulder 117 of the body bolster 11. At their lower ends, the members C and D are provided with outstanding flanges 129—129 in all respects similar to the flanges 29—29 of the members A and B.

The inner side of the member D presents a sub-

stantially flat face 130, which is vertically disposed, while the inner side of the member C is provided with a relatively short, vertical, flat face 139 at its lower end, and is cut away above said face 139, as shown, to present an elongated flat face 140, which is inclined away from the face 130 of the inner side of the member C and extends approximately to the flange 128 at the upper end of said member C where the inner side presents a substantially flat, vertical face 141. At the upper end thereof, the member D is provided with a laterally inwardly projecting lug 134 which bears on the flat face 141 of the member C to hold the upper ends of the sectional pin spread apart. The flange 131 of the member D is undercut, or beveled, as indicated at 142, and the upper end at the inner side of the member C is beveled, or inclined, as indicated at 143, to facilitate assembly of the pin with the bolster, these beveled portions forming cam faces which cooperate during assembling of the mechanism to spread the members apart and bring the head 128 at the upper end of the member C over the shoulder of the bolster. The lower ends of the members C and D are held spread apart in the applied condition of the pin by engagement between the inner side of the lower end portion of the member D with the vertical face 139 of the enlarged lower end of the member C. In applying and removing the members C and D, the same procedure is followed as hereinbefore described in connection with the pin composed of the members A and B illustrated in Figures 1 to 8 inclusive.

Although the improved center pins illustrated in Figures 1 to 8 inclusive and Figure 10 have been shown as arranged to be applied from underneath the truck bolster, it will be evident that the same may be arranged to be applied from above the body bolster downwardly through the bolster opening by reversing the members end for end, as shown in Figure 9, that is, with the pin, as a whole, inverted. In other words, the pin formed by the members A and B will have the flanges 29-29 at the top and the flanges 28-28 at the bottom, and the pin formed by the sections C and D will have the flanges 129-129 at the top and the flanges 128-128 at the bottom.

As will be evident from the preceding description taken in connection with the drawings, in my improved design of center pin construction, advantage is taken of the usual play or clearance provided between the heads of the pin and the shoulders of the bolsters to permit relative longitudinal displacement of the members of the sectional pin in assembling the same with the bolsters. It is further pointed out that by so designing the pin that the members composing the same are insertable within the center pin receiving openings of the bolsters one at a time and in succession and taking advantage of the usual clearance or play provided between the shoulders of the bolsters and the heads of the members of the pin, the number of members making up the complete expandible pin may be reduced to the minimum, or two in number, and yet give the maximum overlap of the heads with respect to the shoulders at the pin receiving openings of the bolsters to provide the required strength.

I have herein shown and described what I now consider the preferred manner of carrying out my invention, but the same is merely illustrative and I contemplate all changes and modifications that come within the scope of the claims appended hereto.

I claim:

1. In car construction, the combination with body and truck bolsters having aligned center pin receiving openings having surrounding abutment shoulders; of a two part sectional center pin insertable in said openings, said pin being split lengthwise into two sections, one of said sections comprising an elongated member having laterally outwardly projecting flanges at opposite ends adapted to engage with said abutment shoulders and a laterally projecting lug on the inner side thereof at one end of the pin, and a second elongated member having laterally outwardly projecting flanges at opposite ends, and a laterally projecting lug on the inner side thereof at the opposite end of the pin, the lug of said first named member bearing on the inner side of said second named member, and the lug of said second named member bearing on the inner side of said first named member to hold said members spread apart and laterally separated between said lugs, said members being lengthwise displaceable to disengage said lugs and permit contraction of said pin, the bearing engagement between the inner sides of said members and said lugs being on flat vertical faces.
2. In car construction, the combination with body and truck bolsters having aligned center pin receiving openings; of a two part sectional center pin insertable in said openings, one of said parts comprising an elongated member having heads at the top and bottom ends, said member having a flat vertical inner side face and a laterally inwardly offset enlargement extending from said side face at the upper end of said member, said enlargement having a flat vertical inner side face and an inclined underneath edge face, the other of said parts comprising a second elongated member having heads at the top and bottom ends, said second named member increasing in thickness toward its lower end and having short, vertical, flat, inner side faces at its upper and lower ends connected by an elongated, inclined, inner side surface, said lower vertical side face of said second named member bearing on the flat vertical inner side face of said first named member and said upper vertical face of said second named member abutting the vertical inner side face of the enlargement of said first named member, said second named member having the inner upper corner beveled, said beveled portion being engageable with said inclined underneath edge face of the enlargement of said first named member to cam the upper ends of said members apart upon relative lengthwise displacement of said members with respect to each other.
3. In car construction, the combination with body and truck bolsters having aligned center pin receiving openings; of a two-part sectional center pin insertable in said openings, each section comprising a shank member extending through said openings and laterally outwardly projecting heads at opposite ends of said shank portion; and a laterally projecting inner flange at one end of each member of the pin, the flanges of said respective members being at opposite ends of the pin, each inner flange engaging the inner side of the other member to hold said members spaced apart between said inner flanges, said engagement being on flat vertical faces.
4. In car construction, the combination with body and truck bolsters having aligned center pin receiving openings and abutment shoulders at said openings; of a two-part sectional pin in-

sertable in said openings, each part comprising an elongated member having heads at opposite ends adapted to overlie said shoulders to prevent separation of the bolsters; and a lateral enlargement at one end of each member, said enlargements of said respective members being at opposite ends of the pin, the enlargement of each member having engagement with the inner side of the other member, said engagement being on flat vertical faces.

5. In car construction, the combination with body and truck bolsters having aligned center pin receiving openings and an abutment shoulder surrounding each opening; of a two-part sectional pin insertable in said openings, each part comprising an elongated member having laterally outwardly projecting heads at opposite ends cooperating with the shoulders of said openings; and a laterally inwardly offset section on the inner side of each member at one end thereof, said offset section of one of said members being at the upper end of the pin and the offset section of the other member being at the lower end thereof, the offset section of each member having flat bearing engagement with the inner side of the other members to hold said member spread apart and separated between said offset sections, said engagement being on flat vertical faces.

6. In car construction, the combination with body and truck bolsters having aligned center pin receiving openings, each opening being surrounded by an abutment shoulder; of a two-part sectional pin insertable in said openings, said pin being headed at opposite ends to cooperate with said shoulders, respectively, said pin being split lengthwise into two members, each member having an offset lateral enlargement at one end thereof on the inner side of the same, said enlargements of said two members respectively being at opposite ends of the pin, the enlargement of each member bearing on the inner side of the other member to hold the members spread apart and separated between said enlargements, the engagement between said enlargements and said inner sides being on flat vertical faces.

7. In car construction, the combination with body and truck bolsters having aligned center pin receiving openings, each opening being surrounded by an abutment shoulder; of a two-part sectional pin insertable in said openings, said pin being headed at opposite ends to cooperate with said shoulders, said pin being split lengthwise into two members, one of said members presenting a flat vertical face portion on the inner side at the upper end thereof and having a laterally projecting lug on the inner side at the lower end thereof presenting a flat vertical inner face, said other member presenting a flat vertical face portion on

the inner side at the lower end thereof and having a laterally projecting lug on the inner side at the upper end thereof presenting a flat vertical inner face, the flat face of the lug of each member being in abutment with the flat face of the other member to hold said pin spread apart with the portions thereof between said lugs laterally spaced with respect to each other.

8. In car construction, the combination with body and truck bolsters having aligned center pin receiving openings, each opening having a surrounding abutment shoulder; of a two-part sectional pin insertable in said openings, each part comprising an elongated member headed at opposite ends to cooperate with said shoulders, each of said members having the inner side thereof provided with a flat vertically extending face at one end and an inwardly projecting lug at the other end, said lug having a flat vertically extending inner face, the lug of each member being in abutment with the flat face of the other member to hold said members separated between said lugs and maintain the pin spread apart with the heads of the two members overhanging the shoulders of the pin receiving openings, said lugs having cam faces engaging said members to spread the same apart upon relative lengthwise displacement of said members with respect to each other.

9. In car construction, the combination with body and truck bolsters having aligned center pin receiving openings, each of said openings being surrounded by an abutment shoulder; of a two-part sectional center pin insertable in said openings, said pin being split lengthwise into two sections, one of said sections comprising an elongated member having laterally outwardly projecting flanges at opposite ends cooperating with said shoulders of the openings, and a laterally projecting lug on the inner side thereof at one end of the pin, and a second elongated member having laterally outwardly projecting flanges at opposite ends cooperating with said shoulders of the openings, and a laterally projecting lug on the inner side thereof at the opposite end of the pin, the lug of said first named member having bearing engagement with the inner side of said second named member on vertically extending flat surfaces, and the lug of said second named member bearing on the inner side of said first named member on vertically extending flat surfaces to hold said members spread apart and laterally spaced apart between said lugs, and inclined guide surfaces on the inner sides of said members at the inner ends of said lugs for camming said members apart upon relative lengthwise displacement of said members with respect to each other.

GEORGE E. DATH.
